UNITED STATES PATENT OFFICE.

ADAM C. WILLIAMS, OF RAVENNA, OHIO.

DESIGN FOR A TOY BANK.

SPECIFICATION forming part of Design No. 35,306, dated November 19, 1901.

Application filed October 22, 1901. Serial No. 79,605. Term of patent 7 years.

To all whom it may concern:

Be it known that I, ADAM C. WILLIAMS, a citizen of the United States of America, residing at Ravenna, Portage county, and State of Ohio, have invented and produced a new and original Design for Toy Banks, of which the following is a specification, reference being had to the accompanying drawings, forming a part thereof.

Referring to the drawings, Figure I shows my design in elevation. Fig. II shows my design in side elevation. Fig. III is a view of the top.

My design comprises a circular base portion, an oval body portion mounted on the base portion, and a flat top portion.

Referring to the drawings, a represents the circular base portion, b the body portion, and c the top. In the center of the top c is formed a slot c'. To facilitate the description, the body portion may be said to comprise the halves b' and b², which are identical in every particular, and each represents the front and side portions of the head and shoulders of a negro. In the representation the characteristic racial features are exaggerated in order to produce a grotesque effect. The head of the negro is represented as drawn down between the shoulders, so that the shoulders almost touch the ears. The shoulders are covered by a coat, with a collar flaring open at the throat. A slouch-hat covers the top of the head, and the brim of the hat extends out beyond the face and down on the shoulders. The hat and coat thus form a frame or setting for the face. The hat-brim is represented as broken and hanging down over the left temple, disclosing the hair of the negro between the crown and the brim of the hat, while over the right temple the brim is carried high, showing the hair below it. When the halves of the design are assembled, the front view of one face is identical with the front view of the other face; but as viewed from the side the faces appear different, as the right side of one and the left side of the other show at the same side of the design.

The leading feature of my design consists in the new and original configuration as shown in the drawings.

Having described my invention, what I claim as new, and desired to secure by Letters Patent, is—

The design for a toy bank as herein shown and described.

Signed by me at Cleveland, Ohio, this 17th day of October, 1901.

ADAM C. WILLIAMS.
